US00D636890S

(12) **United States Design Patent**
Teks et al.

(10) **Patent No.:** **US D636,890 S**
(45) **Date of Patent:** ** *Apr. 26, 2011

(54) **DISPENSING UTENSIL**

(75) Inventors: **Bradley Donald Teks**, Shelly Beach (AU); **Christian Ruediger**, Diddillibah (AU)

(73) Assignee: **Sands Innovations Pty. Ltd.**, Brisbane (AU)

(**) Term: **14 Years**

(21) Appl. No.: **29/343,717**

(22) Filed: **Sep. 17, 2009**

(51) **LOC (9) Cl.** **24-02**

(52) **U.S. Cl.** **D24/224**

(58) **Field of Classification Search** D24/216, D24/222-226, 231, 232, 169, 116, 117, 115; D10/81, 46.2; D3/203.1-203.8; 422/99, 422/102; D9/424, 695, 696, 697-699, 707-710; D7/589, 643, 653; 222/541.9, 92, 107; 206/229

See application file for complete search history.

(57) **CLAIM**

We claim the ornamental design for a dispensing utensil, as shown and described.

DESCRIPTION

FIG. 1 is a top perspective view of the dispensing utensil with a closure;

FIG. 2 is a top perspective view of the dispensing utensil of FIG. 1 without the closure;

FIG. 3 is a bottom perspective view of the dispensing utensil of FIG. 1;

FIG. 4 is a front end elevational view of the dispensing utensil of FIG. 1;

FIG. 5 is a left side elevational view of the dispensing utensil of FIG. 1;

FIG. 6 is a top plan view of the dispensing utensil of FIG. 1 without the closure;

FIG. 7 is a right side elevational view of the dispensing utensil of FIG. 1;

FIG. 8 is a bottom plan view of the dispensing utensil of FIG. 1; and,

FIG. 9 is a rear end elevational view of the dispensing utensil of FIG. 1.
